UNITED STATES PATENT OFFICE.

EMILE ROMANET, OF GRENOBLE, FRANCE.

FURNACE WITH ROTARY GRATE.

1,371,056.

Specification of Letters Patent.

Patented Mar. 8, 1921.

Application filed June 6, 1918. Serial No. 238,556.

To all whom it may concern:

Be it known that I, EMILE ROMANET, a citizen of the Republic of France, residing at 17 Rue de l'Elysée, Grenoble, Isère, in the Republic of France, have invented new and useful Improvements in Furnaces with Rotary Grates, of which the following is a specification.

This invention relates to boiler and other furnaces having rotary grates, the object being to provide a furnace of this kind the upkeep and attendance of which are easy while deterioration through clinkers is avoided, and regularity of draft through all parts of the grate is insured, as well as perfect combustion over the entire surface of the grate covered by the fuel.

Several ways of constructing a furnace according to the invention and its constituent parts are illustrated in the accompanying drawings by way of example.

Figure 1 is a vertical section of a furnace on the line 1—1 Fig. 3.

Fig. 2 is a front elevation of the same.

Fig. 3 is a horizontal section on the crooked line 3—3 Fig. 1.

Figs. 4 and 5 are respectively a plan and a transverse section of one of the grate elements.

Fig. 6 is a horizontal section of the central fixed trunk or body, on line 6—6 of Fig. 1.

Figs. 7 and 8 are respectively an elevation and a plan of one of the sliding plates or doors bounding the combustion chamber 35 with its controlling members.

Figs. 9, 10 and 11 are respectively a partially longitudinal section, a transverse section and a plan of an actuating device for rotating the grate.

Fig. 12 is a transverse section of a device for raking the fuel, taken on the line C, C Fig. 1.

Fig. 13 is a vertical section of a similar furnace provided with a small auxiliary furnace for the purpose of igniting the fuel.

Fig. 14 is a horizontal section on the line D, D Fig. 13.

The construction represented in Figs. 1 to 12 comprises a central fixed and hollow trunk or body 1 around which can revolve the annular shaped grate a. Beneath this grate a chamber 4 is provided open for the greater part of its periphery from the ground to the level of the grate.

The periphery of the grate rests upon a

series of rollers 5 carried by uprights 6; it is provided with a toothed ring 7 with which gears a pinion 8 to which is imparted an intermittent rotary motion from a suitable source of motive power through the medium of a driving mechanism hereinafter described.

The arrow b indicates the direction of rotation of the grate.

The grate comprises an annular trough 65 composed of two concentric rings 9 and 10 united by radial partitions 11 which divide it into a series of compartments 12. Each of these compartments is closed below by a bottom in the form of a hopper 13 having 70 a discharge aperture 14 normally closed by a door. This door opens downward upon a hinge 16 and is provided with a roller 17 which can run upon a circular rail 18, thus sustaining the door in its closed position. 75 At a point in its circumference the rail 18 is mutilated and thereby permits the door 15 to open by its own weight to allow the ash and cinders to fall which have been received in the compartment 12 during the 80 preceding revolution of the grate.

Above the grate are placed the radially disposed bars 19. Each bar is preferably of trapezoidal shape as shown at Fig. 4; it consists of longitudinal portions 19^a placed 85 at a small angle to one another and joined at their ends and also, if required at one or more intermediate points by transverse parts 19^b; each longitudinal member is provided on both of its lateral faces with projections 19^c increasing in length from the center toward the periphery of the grate; so that the complete bar has the form of a ring-segment.

Around the grate is arranged a metal ring 95 50 resting upon the uprights 6 and supporting a brick wall 20 of the grate; the ring 50 is divided into several parts in order that it shall not get out of shape through the expanding action. The wall 20 of the grate 100 has at 20^a a bridge and, at the opposite side of the latter, openings 21, 22, 23 provided with doors 21^a, 22^a, 23^a. Between the said openings and the bridge is placed a front wall of brickwork 24 supported above the 105 grate and the central trunk or body 1 by a reinforcing plate 25, a space being left between the under side of the said wall and the top of the grate.

The combustion chamber occupies only a 110

part of the circular space above the grate; it is bounded at the side of the front by two partitions formed by sliding plates or doors 26 and 27 arranged radially between the 5 openings 21, 22, 23 and movable in guides 28, 29.

In the space between the plates 26, 27 outside the wall 24 is placed a coal hopper 31 the bottom of which opens over the grate 10 against the plate 26 and can be more or less obstructed by the latter.

The plate 27 is designed to close the combustion chamber on the side where the fuel issues and, also, to keep back the coal not 15 yet consumed at the surface of the bed of fuel, the height of this plate being regulated so as to allow, as far as possible, only slag and clinker to pass over the grate.

Between the hopper 31 and the plate 27 is 20 placed a scraping device 32 which extends in a slightly oblique direction with relation to the radii of the grate above the latter and above the sill of the opening 22. This device is adapted to clear the grate from the 25 residues of combustion passed beneath the plate 27 and to bring them into a discharge aperture 33 provided in the sill of the opening 22; these residues fall into a receptacle 34 placed beneath the aperture 33.

30 The air required for combustion is conducted from a blower (not shown) into the compartments 12 through several channels 35^a, 35^b, 35^c, 35^d placed in the ground, and opening under the trunk or body 1, the said 35 air then rising through conduits 36^a, 36^b, 36^c, 36^d formed by partitions 3^a, 3^b, 3^c, 3^d, in the interior of the trunk or body, then through openings 37^a, 37^b, 37^c, 37^d, provided in the periphery of the trunk or body, and openings 40 38, in the inner ring 9 of the grate. The openings 37^a to 37^d are so placed as to feed air only to the compartments 12 situated beneath the combustion chamber, so that the compartments corresponding to the 45 intervening space (front side) between the sliding plates or doors do not receive the forced draft. The circular rail 18 is mutilated just beneath this intervening space so that the compartments open downward and 50 allow their clinkers to fall at the moment when they are not receiving air.

The different channels 35^a, 35^b, 35^c, 35^d, are provided with sliding dampers 39^a, 39^b, 39^c, 39^d, respectively which allow of regulating the supply of air through the sections of the grate corresponding to the openings 37^a, 37^b, 37^c, 37^d. This arrangement allows of accelerating or slackening the combustion at the points where it is thought advisable.

60 In order to prevent any downward escape of air between the trunk or body and the grate, a sand joint is provided as follows: the trunk or body 1 carries at its periphery an annular trough 40 containing fine sand 41 65 into which dips a rib 42 extending down-

ward from the ring 9, there being sufficient play between the said rib and the sides of the trough to avoid friction.

A similar sand joint can, if required, be also provided between the outer ring 10 and 70 the wall 20 or the ring 50.

To prevent friction between the grate and the trunk or body rollers 43 are mounted on brackets 44 around the trunk or body; a flange 9^a on the ring 9 and concentric there- 75 with rolls against the rollers 43.

45 indicates an arrangement of piping, for water under pressure supplied from a suitable source, carrying short tubes 46 which pass tight through the wall of the 80 trunk or body 1 and have their ends inclined upward and outward, each of the said tubes terminating in a sprinkling nozzle 47. Each time one of the covers 39 of the grate passes in front of the nozzles 47 the jet of water 85 spouting out upward sprinkles the bars 19 and cools them.

Each of the plates 26, 27 can be raised and lowered (Figs. 7 and 8) by means of controlling mechanism comprising for example 90 a vertical rod 48 fixed to the plate and having a screw-threaded part 48^a on which turns a nut 49 which is held vertically in position by a support 51 and which is provided with a toothed ring 52 with which 95 gears a screw 53 fixed on a horizontal shaft 54 designed to be turned by means of a hand wheel 55.

The mechanism for actuating the grate is 100 represented at Figs. 9 to 11. It is designed for the purpose of obtaining a very great ratio between the speed of the driving shaft 56 of the works and the speed of the grate, and for allowing the variation of this ratio 105 within very wide limits and in a continuous manner.

This mechanism comprises a drum 61 having a flat rim or plate on the inner side of which the ends or feet 62 of two levers become jammed. These levers are movable 110 upon pivots 63; they carry at one of their ends the feet 62 and, at their other ends joints connected to the control-lever 64 through the medium of toggles 65 and a sleeve 66 having legs and movable around 115 the shaft 67. Owing to the unsymmetrical form of this plate it constitutes a counter-weight which always tends to turn around the shaft 67 in the opposite direction to the arrow.

The lever 64 has a rocking motion given to it upon the shaft 67. When the motion is in the direction of the arrow the jointed ends of the levers 62 are also displaced in the direction of the arrow by the toggles 65. 120 The pivots 63 being moved in the reverse direction, since they are fixed to the plate 68, the feet become jammed onto the rim of the drum and carry it along in their movement without any possibility of slipping. 125 130

When the movement of the lever 64 is reversed the jointed ends of the levers 62 are displaced in the opposite direction to the arrow and release the feet; but the counter-weight-plate carrying the pivots 63 along in the same direction, the feet remain in contact with the rim of the drum by the simple pressure due to the counterweight of the plate; this pressure may be as weak as desired and such that the feet do not carry the plate backward. The continuity of contact thus obtained prevents any loss of motion at each movement of the drum.

The lever 64 is jointed to a sleeve 69 placed free upon the screw-threaded end of an eccentric rod 70. This rod carries a fixed nut 71 and a movable hand wheel nut 72 the displacement of which modifies the stroke utilized by the lever 64. This stroke can therefore vary from the full stroke of the eccentric to zero, using any of the intermediate valves. The advance of the feet 62, and consequently the angular speed of the drum 61, will vary in the same proportions. The interposition of springs or spring washers 73 reduces the shocks of the nuts 71 and 72 on the sleeve 69.

A safety device for preventing breakage, consisting of a bolt 74 of a given section, connecting the boss of the lever 64 to the sleeve 66, obviates rupture of any part, whether of the mechanism that it is intended to actuate, or of the change-speed apparatus.

The intermittent rotary motion of the drum 61 is transmitted to the grate through the medium of the pinion 61^a fixed to the drum and of a wheel 8^a keyed on the shaft of the pinion 8.

The raking device 32 (Figs. 1, 3 and 12) consists of an endless chain 32^a passing around chain wheels 75, 76, carrying a series of rakes 32^b and brushes 32^c movably secured to the chain-links.

The wheel 75 is fixed on a shaft in two parts 77^a, 77^b carrying a pinion 78 placed beneath the ring 50; this pinion gears with a wheel 78^a fixed to a bevel pinion 79 and the latter gears with another bevel pinion 79^a fixed on a shaft 80 which carries another pinion 81 gearing with the toothed ring 7. During the rotation of the grate, the rotary motion is transmitted by the above described gear to the wheel 75 which carries along the chain 32^a. The shaft 77 is held at top and bottom by bearings or supports 82, 83, which are connected to the ring 50. On the other hand, the wheel 76 turns freely upon a shaft 84 fixed in a support 85 which slides in a guide 86^a fixed to the support 83, and this sliding support is united to the end of a horizontal rod 86 the opposite end of which is screw-threaded and screws in the support 83. By screwing this rod the required tension can be put upon

the chain. By slackening the two bolts 83^a which secure the support 83 upon the ring 50, the raking device can be removed in one operation while only leaving in position its control-mechanism situated beneath the ring 50. To this end the shaft portions 77^a, 77^b are united by a key 77^c and a ring 77^d so that they can easily be separated from each other; moreover, the inner end of the guide 86^a is simply inserted between two projections 25^a on the plate 25 and are thus conveniently supported above the grate.

The furnace with rotary grate thus constructed combines numerous advantages; the grate is well equilibrated and can turn freely on the rollers 5 and 43. All the mechanism whereby it is actuated is entirely visible and easily accessible. The admission of the air at the different points of the grate can be regulated as desired as well as the speed of rotation, which allows of using any kind of fuel to the best advantage. The said joints insure tightness and prevent the escape of air and dust outside the furnace. The plates of the furnace, the bars and other parts of the grate can freely expand. They are, besides, kept at a moderate temperature by the water sprinkling arrangement. The slag received in the rotary compartments 12 is automatically discharged at a given point of the rotation. It is the same with regard to the cinders and clinkers which are eliminated by the raking device 32 so that the grate always remains in proper condition for the air to pass through it.

In the modification illustrated in Figs. 13 and 14 the furnace only differs essentially from that illustrated with reference to Figs. 1 to 12 by the addition of a small auxiliary furnace E which serves to insure the ignition of certain kinds of fuel which are very poor in combustible materials.

This small furnace comprises, for example, a fixed grate 87 on which can burn wood or coal having a long flame. It is so placed that the heat given off from the fuel on the grate 87 is deflected by the arch 88 on to the coal which passes beneath the sliding plate or door 26. This heat first causes a distillation to begin and then the ignition of the distilled gases and carbon.

89 indicates the charging door of the furnace E and 90 the ash pit door.

Instead of a coal furnace E an oil or gas furnace can be employed.

In grates constructed according to the herein described invention the combustion surface is horizontal; but the bars can be so arranged that the combustion surface is conical, the periphery being higher or lower than the center.

I claim:

1. In a rotary-grate furnace, the combination of an annular grate composed of a series of sections, each section having a kind of

1
hopper, grate bars over top of the said hopper and a discharge trap at the bottom of the hopper, and means for controlling the opening and closing of the said traps during the course of each revolution of the grate.

2. In a rotary-grate furnace the combination of central fixed trunk or body having air passages within it opening at the top at 10 its periphery, an annular grate revolving around the said trunk or body, the said grate comprising an annular trough, radial partitions forming compartments in the said trough and bars covering the said compartments, the inner wall of the said grate being adjusted to turn around the trunk or body and having apertures adapted to pass in front of upper openings in the said passages in the trunk or body.
3. In a rotary-grate furnace the combination of a central fixed trunk or body having air passages within it opening at the top at 15 its periphery, annular grate revolving around the said trunk or body, the said grate comprising an annular trough, radial partitions forming compartments in the said trough and bars covering the said compartments, the inner wall of the said grate being adjusted to turn around the trunk or 20 body and having apertures adapted to pass in front of upper openings in the said pas-

25 sages in the trunk or body and means for regulating the admission of air separately in the passages of the trunk or body.

4. In a rotary-grate furnace the combination of a grate having a circular row of gear teeth, a pinion engaging with the said teeth and change-speed means of control for operating the said pinion, the said means of control comprising a spindle, a drum and a 30 lever and a plate rotatably mounted upon the said spindle, pivoted levers on the said plate, the said levers having at their outer ends feet adapted to bear against the inner periphery of the said drum, the inner ends 35 of the said levers being connected to the said lever, and means for imparting to the said lever an adjustable to-and-fro motion, the said plate being unsymmetrical so that its weight tends to keep it or to return it to a 40 given position of rest.

5. In a rotary-grate furnace, a raking device comprising a horizontal guide, a fixed bearing at one end of the said guide, a bearing movable along the said guide, vertical 45 shafts in the said bearings, chain wheels upon the said shafts, a chain passing around the said wheels, raking members upon the said chain and means for regulating the position of the said movable bearing upon the 50 said guide.

EMILE ROMANET.
